UNITED STATES PATENT OFFICE.

CHARLES M. HORTON, OF ELIZABETH, NEW JERSEY, ASSIGNOR TO THE SINGER
MANUFACTURING COMPANY, A CORPORATION OF NEW JERSEY.

LOOP-TAKER MECHANISM FOR SEWING-MACHINES.

1,107,308.

Specification of Letters Patent. Patented Aug. 18, 1914.

Application filed October 9, 1909. Serial No. 521,815.

To all whom it may concern:

Be it known that I, CHARLES M. HORTON, a citizen of the United States, residing at Elizabeth, in the county of Union and State 5 of New Jersey, have invented certain new and useful Improvements in Loop-Taker Mechanisms for Sewing-Machines, of which the following is a specification, reference being had therein to the accompanying drawings.

This invention relates to an improvement in that class of sewing machines comprising a reciprocating needle to which is imparted lateral jogging movements, either successively as in the production of buttonhole or overseam stitching, or at intervals, as in certain classes of embroidery work, combined with a loop-taker moving in a path substantially parallel at the loop-seizing position with the plane of lateral movement of the needle whereby needle-thread loops are seized and concatenated with other needle-thread loops or with a lower thread or threads; and it has for its object to insure a uniform relation of the needle and loop-taker at the time the latter seizes thread loops from the former, so as to insure the effective operation of the stitch-forming mechanism.

In its preferred embodiment, the improvement is applied to an oscillating shuttle machine in which the shuttle-actuating shaft has loosely mounted thereon a sleeve provided with the usual actuating means connected with the main-shaft for imparting thereto oscillatory movements of the amplitude normally required for the shuttle movements, this sleeve having fulcrumed thereon an angular lever one arm of which is pivotally connected with a fixed collar upon the shuttle-actuating shaft, while the extremity of the other arm of said lever is confined within a movably mounted raceway adapted to be tilted by a connection with the swinging needle-frame in which the needle-bar is journaled to reciprocate.

In the accompanying drawings, Figure 1 is a sectional side elevation of a Singer zig-zag feed-up-the-arm machine embodying 50 the present improvements, Fig. 2 a plan of the same with the bracket-arm partly in section at the center of the main-shaft, and Fig. 3 an elevation of the front end of the machine. Fig. 4 is a transverse sectional

elevation, upon a larger scale, through the 55 upright portion of the bracket-arm, looking forwardly. Fig. 5 is a perspective view, upon a still larger scale, of the principal part of the shuttle-actuating mechanism, and Fig. 6 a perspective view of a portion 60 of said mechanism.

As herein represented, the frame of the machine comprises the base 1 from which extends laterally the cylindrical horn or work-supporting arm 2, and from which rises the hollow standard 3 of the bracket-arm formed with the horizontal tubular portion 4 overhanging the horn 2 and terminating at the forward end in the head 5. The main-shaft 6 is journaled as usual in the 70 overhanging arm 4 and carries the balance-wheel 7 and belt-wheel 8.

Upon the aligned fulcrum-pins 9 and 10 within the head 5 is journaled the swinging needle frame 11 in which is mounted the 75 needle-bar 12 carrying the needle 13, the needle-bar deriving its vertical reciprocatory movements from a crank-pin on the cam-cylinder 14, fixed upon the forward end of the main-shaft, through the link 15, in a 80 well-known manner.

The needle-frame 11 has a forked lug 16 to which is secured by a universal joint connection one end of a rod 17 whose opposite end is adjustably connected by means of a 85 clamp-screw 18 with the grooved segmental jog-lever 19 fulcrumed at 20 upon the arm 4 and having a stud 21 entering the groove 22 of the cam-cylinder 23 journaled upon a screw-stud 24 and having upon its rearward 90 face a bevel-gear 25 meshing with and driven by means of the smaller bevel-wheel 26 fixed upon the main-shaft 6. The proportions of the bevel-wheels 25 and 26 and the form of the cam-groove 22 are such that 95 the needle-frame 11 assumes opposite extreme positions for each successive thrust of the needle, as is usual in this class of machines.

The main-shaft 6 is provided with a second bevel-wheel 27 meshing with a similar wheel 28 fixed upon the inner end of a transverse shaft 29 which is mounted in a bearing boss 30 upon the front side of the arm 4, this transverse shaft carrying the hand-wheel 31 which is provided for convenience in handling the machine.

In the production of stitches, the needle

13 cooperates with a shuttle 32, shown in the drawings provided with a barrel-shaped thread-case 33 and fitted to oscillate within a raceway 34 in the forward end of the work-supporting horn 2. In the operation of the machine, the throat and heel of the shuttle are alternately engaged by the two horns of the shuttle-driver 35 fixed upon the forward end of the shuttle-actuating rock-shaft 36 5. The described connection with the needle-frame of the raceway arm 64 causes the latter, which is normally in upright position with its raceway 63 in a plane perpendicular to the loop-taker rock-shaft 36, to be tilted 70 slightly out of normal position for each alternate stitch corresponding with the jog of the needle. When the raceway 63 is in normal upright position, the rocking of the sleeve 40 by its connection with the actuating crank 53 of the main-shaft causes the extremity of the arm 57 of the angle-lever to move in a plane perpendicular to the rock-shaft 36, the forked lug 38 of the collar 37 being constantly propelled by the other arm 75 10 which is journaled in suitable bearings within the work-supporting horn. Upon the rearward end of the rock-shaft 36 is the collar 37 formed with a forked lug 38 and with a tubular hub 39 upon which is mounted the loose sleeve 40 provided with the crank-arm 15 41. The arm 41 has a crank-pin which carries the slide-block 42 confined thereon by means of the screw 43 and washer 44, which slide-block is embraced by the forked arm 45 of a rock-lever whose hub 46 is secured upon a sleeve 47 mounted upon the fulcrum-pin 48 fixed in the base 1 of the machine parallel with the shaft 36. An oppositely extending arm 49 of the rock-lever carries a pin 50 embraced by the lower end of a pitman-rod 51 whose opposite end is provided with a strap 52 embracing an actuating crank 53 in the rearward end portion of the main-shaft 6, from which, with the intermediate connections above described, the rocking sleeve 40 derives uniform oscillatory movements. 20

Upon the radial fulcrum-stud 54 carried by the rocking sleeve 40 is mounted the hub 55 of an angle-lever having arms 56 and 57 each provided with a ball-stud, 58 and 59, respectively, the hub 55 being confined upon its stud by means of the screw 60. To the ball 58 is fitted a socket in the divided slide-block 61 which is in turn fitted to the recess in the forked lug 38 of the fixed collar 37. 25

Upon the ball-stud 59 is fitted a second divided and socketed slide-block 62 entering a raceway 63 in a segmental arm 64 whose hub 65 has projecting in one direction, in the plane of the raceway 63, a stud 66 with conical center-screw socket 67 in its outer extremity. At the other end of the hub 65 is a lug 68 similarly formed with a conical center-screw socket 69 arranged in alignment with the socket 67, these sockets being entered by the points of center-screws 70 and 71, respectively, mounted in the base 1. Fixed upon the stud 66 is an upwardly extending crank-arm 72 carrying upon its upper end a screw-pin 73 upon which is mounted a block 74 entering a fork 75 in the lower extremity of the depending arm 76 of a vibrating lever which is fulcrumed upon a fixed screw-stud 77 and has an upwardly extending arm 78 to which is pivotally connected one end of a pitman-rod 79 whose opposite end has a forked head 80 embracing and pivoted upon a lateral lug 81 of the needle-frame 11. 30

The described connection with the needle-frame of the raceway arm 64 causes the latter, which is normally in upright position with its raceway 63 in a plane perpendicular to the loop-taker rock-shaft 36, to be tilted 70 slightly out of normal position for each alternate stitch corresponding with the jog of the needle. When the raceway 63 is in normal upright position, the rocking of the sleeve 40 by its connection with the actuating crank 53 of the main-shaft causes the extremity of the arm 57 of the angle-lever to move in a plane perpendicular to the rock-shaft 36, the forked lug 38 of the collar 37 being constantly propelled by the other arm 56 of said angle-lever in fixed relation with the crank-arm 41 of the sleeve 40. When, however, the raceway arm 64 assumes its inclined position corresponding with the other extreme position of the needle, the angle-lever 56 57 is turned slightly upon its fulcrum-stud 54 so as to change the relative positions of the forked lug 38 and crank-arm 41, the loop-taker point being advanced correspondingly with the amplitude of lateral movement of the needle. The shift of the raceway arm 64 from one to the other of its extreme positions being effected with the lateral movement of the needle-frame 11 while the needle is in upper position and the shuttle is in cast-off position, the slide-block 62 is at such time in its lower position, nearest the axis of oscillation of the hub 65, and so near such axis that the slight tilting motion of the arm 64 is not sufficient to appreciably change the cast-off position of the shuttle, but as the shuttle mechanism recedes from cast-off position to loop-taking position, the angle-lever arm 57 with its slide-block 62 assumes a position above the rock-shaft 36 where it receives its greatest effect from the raceway 63, and hence the loop-seizing position of the shuttle-point is changed correspondingly with the lateral positions of the needle, so that the loop-taker 100 cooperates with the needle under precisely the same conditions in each of its lateral positions, regardless of the amplitude of jog of the needle. It will be observed that by changing the adjustment of the needle-frame engaging rod 17 with the vibrating segment-lever 19, the amplitude of lateral needle movement crosswise of the horn 2 may be varied, the operation of the shuttle movement compensating device being similarly effected, as the latter is actuated from a connection with the needle-frame. 105

From the above description of the operation of this mechanism, it will be seen that the advance and recession of the initial position of the loop-taker point as it is about to commence its operative movement causes the relative positions of the needle-eye and looper point to maintain a fixed relation, the point of the loop-taker in every case seizing 110 120 125 130 135 140 145 150 155 160 165 170 175 180

the needle-loop at precisely the same distance above the needle-eye, so that the needle may have a uniform depth below the throat-plate of minimum length to insure the proper formation and seizure of its thread-loops by the loop-taker.

Journalized in the head 5 of the bracket-arm is the usual presser-bar 82 pressed normally downward by means of a spring 83 interposed between its upper bearing and a fixed collar 84 thereon and carrying the presser-foot 85 opposed to the feed-dog 86 affixed to the forward end of the feed-bar 87 and having a pressure spring 88 resting upon the under side of the throat-plate 89. The feed-bar is pivotally connected at its rearward end with an upwardly extending arm 90 of a transverse rock-shaft 91 journalized in the base 1 of the machine frame and having a rearwardly extending arm 92 with a universal joint connection with the lower end of the link-bar 93 formed at its upper end with a yoke 94 embracing the triangular feed-actuating cam 95 upon the main-shaft. The link-bar has in its yoked portion a stud 96 embraced by one end of a link 97 whose opposite end is fulcrumed upon a screw-stud 98 upon the depending arm 99 of the feed-regulator angle-lever having a fixed fulcrum 30 at the junction of its arms and provided with the lateral arm 100 by which it is shifted in a well-known manner to change the position of the fulcrum-stud 98 of the supporting link 97 for the link-bar 93 for determining the extent of up-and-down movement of this cam-controlled member in communicating through the connections above described the reciprocatory movements of the feed-bar 87.

40 The shank of the feed-dog 86 rests upon the top of a yoked slide 101 to which rising and falling movements are imparted by a suitably formed cam 102 upon the shuttle-actuating rock-shaft 36.

45 The tension device 103 may be of any usual or suitable construction, as also the take-up 104 which is herein shown comprising a lever actuated from the cam-groove 14^x of the cam-cylinder 14.

50 Having thus set forth the nature of the invention, what I claim herein is:

1. In a sewing machine, the combination with the loop-taker, of actuating means therefor, controlling means interposed between said loop-taker and its actuating means and adapted to cause the loop-taker to move at one speed between loop-seizing and cast-off positions in one stitch-forming cycle and at a different speed in the next succeeding stitch-forming cycle while maintaining a substantially uniform cast-off position for all stitch-forming cycles, and a take-up cooperating with said loop-taker at the common cast-off position in consecutive stitch-forming cycles, whereby the release

and drawing up of all thread-loops seized and distended by the loop-taker will be effected under the same conditions.

2. In a sewing machine, the combination with a loop-taker, of uniformly acting means for imparting thereto to-and-fro operative movements, and means for varying the length of traverse of said loop-taker toward and from a substantially fixed limit.

3. In a sewing machine, the combination with a reciprocating and laterally movable needle, a loop-taker, and needle-reciprocating and loop-taker actuating means adapted to effect the coöperation of the loop-taker with the needle in the same stage of the latter's reciprocatory movements in each stitch-forming operation, of means controlled in its degree of action by the lateral position of the needle and adapted to automatically vary the length of traverse of the loop-taker between loop-seizing position and a cast-off position which is substantially fixed.

4. In a sewing machine, the combination with a reciprocating and laterally movable needle, a loop-taker confined to movement in a fixed plane, a take-up, and needle-reciprocating and take-up actuating means, of actuating means for imparting to the loop-taker loop-seizing movements, a connection between said loop-taker and its actuating means whereby the loop-taker is caused to assume a substantially uniform cast-off position as the take-up begins to perform each thread-drawing action, and means adapted to control the loop-seizing movements of the loop-taker to maintain a substantially uniform loop-seizing position of the loop-taker relatively to the needle correspondingly with the latter's lateral positions in consecutive stitch-forming operations.

5. In a sewing machine, the combination with a needle, means for imparting thereto reciprocating movements, and means for imparting to said needle lateral jogging movements, of a reciprocatory loop-taker, a shaft for communicating operative movements thereto, a driving element loosely mounted on said shaft, actuating means for imparting uniform operative movements to said driving element, a connection between said driving element and said shaft, and controlling means acting upon said connection synchronously with the needle-jogging means for varying the position of said driving element upon and relatively to said shaft.

6. In a sewing machine, the combination with a needle, reciprocating means therefor and jogging means therefor, of a circularly moving loop-taker, a shaft for communicating operative movements thereto, a driving element loosely mounted upon and adapted to turn independently of said shaft, actuat-

- ing means for imparting to said driving element circular operative movements, a connection between said driving element and said shaft, and controlling means acting 5 upon said connection synchronously with the needle-jogging means whereby said driving element is shifted relatively to said shaft.
7. In a sewing machine, the combination 10 with a needle, reciprocating means therefor and jogging means therefor, of a circularly moving loop-taker, a shaft for communicating operative movements thereto, a driving element loosely mounted on said shaft, actuating means for imparting to said driving element circular operative movements, a rocking member mounted upon said driving element and connected with said shaft and provided with a lateral arm, a reciprocatory 15 member formed with a raceway embracing said lateral arm of the rocking member, and means acting upon said reciprocatory member synchronously with the needle-jogging means for imparting operative movements 20 thereto in controlling the relation of said shaft with the driving element thereon.
8. In a sewing machine, the combination 25 with a needle, reciprocating means therefor and jogging means therefor, of a circularly moving loop-taker, a shaft for communicating operative movements thereto, a driving element loosely mounted on said shaft, actuating means for imparting to said driving element circular operative movements, a 30 rocking member mounted upon said driving element and connected with said shaft and provided with a lateral arm, a reciprocatory member formed with a raceway embracing said lateral arm of the rocking member and 35 fulcrumed to tilt upon an axis substantially in the plane of and adjacent one side of said raceway, and means acting upon said reciprocatory member synchronously with the needle-jogging means for imparting tilting 40 movements thereto in controlling the relation of said shaft with the driving element thereon.
9. In a sewing machine, the combination 45 with a needle, reciprocating means therefor and jogging means therefor, of a circularly moving loop-taker, a shaft for communicating operative movements thereto, a sleeve loosely mounted upon said shaft and provided with a radial fulcrum-stud, actuating 50 means for imparting to said sleeve circular operative movements, a rocking member mounted upon said fulcrum-stud and having a positive connection with said shaft and a lateral arm in angular relation therewith, a 55 tilting arm formed with a raceway embracing the lateral arm of said rocking member and movable upon an axis adjacent one side of said raceway and transverse to the loop-taker shaft, and means connected with the needle-jogging means for tilting the raceway 60 65 70 75 80 85 90 95 100 105
10. In a sewing machine, the combination with a needle, reciprocating means therefor and jogging means therefor, of an oscillatory loop-taker, a rock-shaft for communicating operative movements thereto, a sleeve loosely mounted upon said rock-shaft and provided with a radial fulcrum-stud, actuating means for imparting to said sleeve circular operative movements, an angle-lever mounted upon said fulcrum-stud, a collar mounted upon said rock-shaft and provided with a lug operatively connected with one arm of said angle-lever, a tilting arm formed with a segmental raceway embracing another arm of said angle-lever and mounted for movement upon an axis adjacent one side of said raceway, and means connected with the needle-jogging means for tilting the raceway arm.
11. In a sewing machine, the combination 110 with a needle, reciprocating means therefor and jogging means therefor, of an oscillatory loop-taker, a rock-shaft for communicating operative movements thereto, a sleeve loosely mounted upon said rock-shaft and provided with a radial fulcrum-stud, actuating means for imparting to said sleeve circular operative movements, an angle-lever mounted upon said fulcrum-stud, a collar mounted upon said rock-shaft and provided with a lug operatively connected with one arm of said angle-lever, a tilting arm formed with a segmental raceway embracing another arm of said angle-lever and mounted for movement upon an axis adjacent one side of said raceway, a vibratory lever rigidly connected with the raceway arm, a rock-lever mounted upon a fixed fulcrum and having an arm pivotally connected with said vibratory lever, and a connection intermediate said rock-lever and the needle-jogging means whereby tilting movements are imparted to the raceway arm for varying the relation of said rock-shaft to the sleeve mounted thereon.
